UNITED STATES PATENT OFFICE.

FRANK T. WOOD, OF ALLSTON, MASSACHUSETTS, ASSIGNOR TO AMERICAN BANK
NOTE COMPANY, OF NEW YORK, N. Y., A CORPORATION OF NEW YORK.

CHECK BOOK.

Application filed December 28, 1922. Serial No. 609,387.

To all whom it may concern:

Be it known that I, FRANK T. WOOD, a subject of the King of the United Kingdom of Great Britain and Ireland, residing at 5 Allston, in the county of Suffolk and State of Massachusetts, have invented certain new and useful Improvements in Check Books, of which the following is a specification, reference being had therein to the accompanying drawings, which form a part thereof.

My invention relates to check books, and more particularly to a check book in which a pad, or block, of checks may be removably mounted with relation to a cover so as to 15 permit the removal of the stubs of the checks from the cover and the substitution of a fresh pad, or block, of checks therefor.

It is customary for banks, and other financial institutions, to furnish their customers 20 with check books, so that with an active checking account, the expense entailed by a bank in the gratis distribution of check books is material.

Various types of check books have heretofore been devised for the purpose of permitting the continued use of a cover after 25 all checks carried within same have been used, a common practice having been to employ refills composed of checks padded together without a cover, and capable of being assembled in a specially constructed cover. The most common expedient has been the use of a cardboard tongue upon the back of the pad or block of checks, adapted to 30 enter a pocket in the lower side cover adjacent the hinge, of the check book. When the number of checks included in a pad is not great, as when foldable check books are used, this form of check book has been found 35 fairly satisfactory in use, although the manner of connecting the pad of checks and the stubs with the cover, permits sufficient freedom of movement of the pad with relation to the cover while in use, to preclude 40 the use of this construction of book for ordinary pocket, or three-on or four-on check books wherein the number of sheets used is ordinarily from fifty to one hundred, and sometimes even more, and the weight of the 45 block is material. With larger and heavier pads the tongue and pocket securing means between the cover and the pad cannot be used, because this means of connection lacks the necessary permanency or rigidity to

properly support the pad while the book is 55 being handled.

By means of a check book embodying my invention, I am enabled to provide a structure in which the removable pad or block of checks and their stubs, whether the latter be attached to the checks, or carried upon an insert sheet when assembled in the cover, will have the same, or possibly even a greater, degree of rigidity than the ordinary check book in which the checks 60 are permanently bound in the cover. Notwithstanding this rigidity of structure, a pad, or block, of checks may be quickly and firmly mounted within the cover, and the stubs as quickly removed therefrom when all the 65 checks have been used to permit the mounting of a new refill pad or block in the cover to replace the pad or block, the checks in 70 which have been used.

A further characteristic of the invention 75 is that the portion of the means carried by the cover for permitting a pad or block of checks to be mounted therein, co-operates directly with the various sheets of the pad or block of checks, and also reinforces the 80 cover adjacent the back and hinge thereof in a manner to prolong the life of the cover.

The pad or block is so secured with relation to the cover that it cannot accidentally escape from the cover during handling of 85 the check book, or in the event that the user should drop the book, and under no circumstances can the pad or block have any such movement with relation to the cover as will interfere with the handling of the 90 book or its use when filling out checks.

In a check book embodying my invention, the cost of the cover, which may be used for a long period and with a large number of pads or blocks, will be but little 95 greater than the cost of the binding of an ordinary check book of the same size, and the cost of the refill pads or blocks will be very materially less than that of a bound check book, and not materially greater than 100 the checks and stubs which enter into the production of an ordinary check book.

The invention consists primarily in a check book embodying therein a protecting cover including therein a back and opposite side covers, one of which is hinged with relation to said back, a metal channel piece carried at the back of said cover, a pad of 105

checks of a thickness to have a sliding fit in said channel piece and consisting of a plurality of superimposed sheets bound together at one edge thereof, and co-operating 5 means carried by said channel piece and formed on said pad or block adjacent the bound edges of said sheets, whereby said pad or block may be removably and rigidly connected with said cover; and in such other 10 novel characteristics as are hereinafter set forth and described, and more particularly pointed out in the claims hereto appended.

Referring to the drawings,

Fig. 1 is a perspective view of a pocket 15 check book embodying my invention;

Fig. 2 is a similar view upon a larger scale, of the cover and the means carried adjacent the back thereof, cooperating directly with the pad or block of checks in 20 securing same to the cover; and

Fig. 3 is a view upon a larger scale, partly in plan and partly in horizontal section, illustrating a portion of a completely assembled check book adjacent the back, and 25 the manner of mounting the pad or block therein and removing it therefrom.

Like letters refer to like parts throughout the several views.

In the drawings, I have shown an embodiment of my invention consisting of an ordinary pocket check book having stiff sides and containing approximately fifty checks 30 with the usual insert stub sheets. It will be readily understood, however, that the application of the invention to larger check books of the three-on and four-on type in which each of the checks is connected directly to a stub, would involve a mere change 35 in the dimensions, and possibly the weight, 40 of the parts of the cover, but would require no material changes in its structural characteristics.

The cover, as shown in the drawings, consists of the upper and lower sides *a* and *b* 45 and a channeled back *c*, which parts have the ordinary cloth cover, forming hinges between said back and said sides. While cloth is shown as being the covering material, it is apparent that if desired a more expensive 50 or a more decorative covering material may be used, since the life of a cover in a check book embodying my invention is determined by the durability of the material entering into same and not by the use of the checks carried and protected thereby. Furthermore, in view of the possibility of a prolonged use of the cover, an issuing bank may prefer to use more expensive and more decorative material for some of its customers, or 55 by way of advertising, particularly as the additional expense of such is not great as compared with the saving which can be effected by the subsequent issue of refill pads or blocks instead of completely bound check 60 books having covers of cheaper materials.

Secured to the channelled back of the cover is a stud or studs *d*, preferably two or more such studs being used, which studs project across the channel of the back at a point or points intermediate the ends thereof, and are preferably firmly secured to a metal channel piece *e* conforming to the channelled back *c* and adapted to seat within same. Said studs are preferably secured to 70 said metal channel piece by having reduced ends passing through openings therein and riveted or upset, said channel piece and said studs thus serving to impart additional 75 rigidity to the back of the cover.

The channel piece *e* is provided at each 80 end of each side, and of the bottom, thereof with extensions *e'* adapted to be closed and crimped upon the edges of the back channel *c* for securing the channel piece *e* permanently in position with relation thereto. 85 While in the drawings, I have shown the crimped extensions as being exposed exteriorly of the covering cloth of the cover, it is apparent that if desired the channel piece *e* may be applied to the back channel 90 *c* before the covering material is applied to the different parts of the cover, and thus conceal the securing means for said channel piece *e*.

The cover heretofore described is adapted 95 to receive a pad or block *f* of checks formed of a plurality of superimposed sheets which may contain one or more impressions, as desired, or be in the form of single checks, or three-on or four-on check sheets, and have 100 the stubs in the form of insert sheets or printed upon the same sheets as the checks. Said sheets are bound together at one edge in any desired manner, although I preferably use wire stitching as indicated at *g* for 105 this purpose, since such stitching possesses greater permanency than other padding means, and will also serve as a reinforcement at certain points of this edge, which is of value when mounting or removing a pad 110 or block from the cover.

The pad or block *f* is of a thickness to permit the portion thereof adjacent the bound edges of the sheets forming same to have a sliding fit within the channel piece *e*, 115 and said pad or block has formed thereon means co-operating with means carried by said channel piece whereby said pad or block may be removably and rigidly connected with the cover.

The various sheets of the pad or block *f* adjacent the bound edge thereof, have formed therein as by punching, a bayonet slot or slots *h* adapted to receive the stud or studs *d*, and form a tongue *i* adapted to 125 pass between a stud *d* and the bottom of said channel piece and thus permit the rapid and convenient removal of the stubs from a cover, and the equally rapid and convenient substitution of a fresh pad or 130

block therefor. The bayonet slots *h* are preferably positioned adjacent the wire stitches *g* so that these stitches may reinforce the thin portion of the pad or block 5 between a portion of the bayonet joint and the bound edge thereof forming the tongue *i* and thus strengthen the connecting means as in the assembled book. While the bulk 10 of the material of the pad with or without the wire stitching *g* will impart considerable strength to the tongues *i* produced as a result of the formation of the bayonet slots, and the close sliding fit of said tongues between the studs *d* and the bottom 15 of the channel piece *e* will ensure the desired rigidity in the connection between the pad or block and the cover, I preferably form the portion of the bayonet slot extending substantially parallel with the bottom 20 of the channel member *e*, upon a slight incline so as to secure a wedging action between the tongues *i* and the studs, which will force the bound edge of the pad or block firmly against the bottom of said 25 channel piece.

With the construction described, in mounting a pad or block in the cover, the open end of each bayonet slot is passed over a stud *d* and the pad thrust toward the bottom 30 of the channel piece *e* in the direction indicated by the arrow 1 in Fig. 3. The pad or block is then moved in the direction of the arrow 2 until it is brought entirely within the side covers *a* and *b*, the wedging 35 action of the bayonet slot forcing the bound edge of the pad firmly against the bottom of the channel piece *e*.

It will be noted that the length of the bayonet slot is such that when the block is 40 thus positioned within the cover, it cannot escape therefrom with the handling of the book, because of the different directions of movement necessary to separate the pad or block from the cover, the sliding fit between the pad or block and the channel *e* and the tight fit of the tongues *i* between the studs *d* and the bottom of the channel piece *e* in the event of the tongues being wedge-shaped. Furthermore, the length of 45 these slots being greater than the distance between the edge of the pad and the adjacent edge of the channel *e* and book side *a* or *b*, in case the book is dropped, and falls upon one edge with sufficient force to cause 50 sliding movement of the pad within the cover, the movement required to bring the pad in a position where the tongues *i* are disengaged from the studs *d* is sufficient to require that the pad extend beyond the edges of the side covers *a* and *b* so that 55 under no circumstances can the pad or block accidentally escape from the cover.

When all of the checks in a pad or block have been used, the stubs, irrespective of

their form, are removed from the cover by 65 a reversal of the steps for inserting a pad or block therein, and a fresh block substituted therefor.

In a check book embodying my invention, the assembled pad or block and cover does 70 not differ in size or appearance from permanently bound checkbooks of the same size and character, and is used in exactly the same manner.

The covers may be conveniently and 75 economically produced without regard to the numbering or other printing upon the checks, and may, if desired, have the name of the bank or its customers embossed, or otherwise impressed thereon, since this small item of cost is not prohibitive when the cover may be used for a long time.

The only operation required in the assembling of the checks in pad or block form, not required in the production of ordinary bound check books, is the punching of the bayonet slots therein, but this is a machine operation and does not add materially to the cost of the pads, and is very much less than the cost of binding such checks in covered book form, particularly with a cloth covering.

It is not my intention to limit the invention to the precise details of construction shown in the accompanying drawings, it being apparent that such may be varied without departing from the spirit and scope of the invention.

Having described the invention, what I claim as new and desire to have protected 100 by Letters Patent, is:—

1. A check book embodying therein a protecting cover including therein a back and opposite side covers, one of which is hinged with relation to said back, a metal channel piece carried at the back of said cover, a pad of checks of a thickness to have a sliding fit in said channel piece and consisting of a plurality of superimposed sheets bound together at one edge 105 thereof, and co-operating means carried by said channel piece and formed of the material of said pad adjacent the bound edges of said sheets, whereby said pad may be removably and rigidly connected with said cover. 110

2. A check book embodying therein a protecting cover including therein a channelled back, opposite side covers, one of which is hinged with relation to said back, and a stud carried by and extending across said channelled back, and a pad of checks of a thickness to have a sliding fit in said channelled back, consisting of a plurality of superimposed sheets bound together at one edge 115 thereof, and having a bayonet slot formed therein adjacent, and opening outwardly of, the bound edges of said sheets 120 to form a tongue of the material of said

pad adapted, by a two-way movement, to interlock with said stud to removably and rigidly connect said pad with said cover.

3. A check book embodying therein a protecting cover including therein a channelled back, opposite side covers, one of which is hinged with relation to said back, and a stud carried by and extending across said channelled back, a pad of checks of a thickness to have a sliding fit in said channelled back, consisting of a plurality of superimposed sheets, a wire stitch binding said sheets together, and a tongue upon said pad formed by a bayonet slot adjacent, and opening outwardly of, the bound edges of said sheets, and so located as to include said wire stitch in said tongue, whereby said tongue is reinforced by said wire stitch and is adapted, by a two-way movement, to interlock with said stud to removably and rigidly connect said pad with said cover.

4. A check book embodying therein a protecting cover including therein a channelled back, opposite side covers, one of which is hinged with relation to said back, and a stud carried by and extending across said channelled back, and a pad of checks of a thickness to have a sliding fit in said channelled back, consisting of a plurality of superimposed sheets bound together at one edge thereof, and having a bayonet slot formed therein adjacent, extending at an incline to, and opening outwardly of, the bound edges of said sheets to form a wedge-shaped tongue of the material of said pad adapted, by a two-way movement, to interlock with said stud to removably and rigidly connect said pad with said cover.

5. A check book embodying therein a protecting cover including therein a channelled back, opposite side covers, one of which is hinged with relation to said back, and a stud carried by and extending across said channelled back, a pad of checks of a thickness to have a sliding fit in said channelled back, consisting of a plurality of superimposed sheets, a wire stitch binding said sheets together, and a wedge-shaped

tongue upon said pad formed by a bayonet slot adjacent, extending at an incline to, an opening outwardly of, the bound edges of said sheets, and so located as to include said wire stitch in said tongue, whereby said tongue is reinforced by said wire stitch and is adapted, by a two-way movement, to interlock with said stud to removably and rigidly connect said pad with said cover.

6. A check book embodying therein a protecting cover including therein a channelled back and opposite side covers, one of which is hinged with relation to said back, a metal channel piece having extensions at each end of each side, and of the bottom,

thereof, folded and crimped upon said channelled back of said cover, and a pad of checks of a thickness to have a sliding fit in said channel piece and consisting of a plurality of superimposed sheets bound together at one edge thereof, and co-operating means carried by said channel piece and formed on said pad adjacent the bound edges of said sheets, whereby said pad may be removably and rigidly connected with said cover.

7. A check book embodying therein a protecting cover including therein a channelled back, opposite side covers, one of which is hinged with relation to said back, a metal channel piece carried by said channelled back, and a stud carried by and extending across said channel piece, and a pad of checks of a thickness to have a sliding fit in said channelled back, consisting of a plurality of superimposed sheets bound together at one edge thereof, and having a bayonet slot formed therein adjacent, and opening outwardly of, the bound edges of said sheets to form a tongue of the material of said pad adapted, by a two-way movement, to interlock with said stud to removably and rigidly connect said pad with said cover.

8. A check book embodying therein a protecting cover including therein a channelled back, opposite side covers, one of which is hinged with relation to said back, a metal channel piece carried by said channelled back, and a stud carried by and extending across said channel piece, and a pad of checks of a thickness to have a sliding fit in said channelled back, consisting of a plurality of superimposed sheets, a wire stitch binding said sheets together, and a tongue upon said pad formed by a bayonet slot adjacent, and opening outwardly of, the bound edges of said sheets, and so located as to include said wire stitch in said tongue, whereby said tongue is reinforced by said wire stitch and is adapted, by a two-way movement, to interlock with said stud to removably and rigidly connect said pad with said cover.

9. A check book embodying therein a protecting cover including therein a channelled back, opposite side covers, one of which is hinged with relation to said back, a metal channel piece carried by said channelled back, and a stud carried by and extending across said channel piece, and a pad of checks of a thickness to have a sliding fit in said channelled back, consisting of a plurality of superimposed sheets bound together at one edge thereof, and having a bayonet slot formed therein adjacent, extending at an incline to, and opening outwardly of, the bound edges of said sheets to form a wedge-shaped tongue adapted, by a two-way movement, to interlock with said stud.

- to removably and rigidly connect said pad with said cover.
10. A check book embodying therein a protecting cover including therein a channelled back, opposite side covers, one of which is hinged with relation to said back, a metal channel piece carried by said channelled back, and a stud carried by and extending across said channel piece, and a pad of checks of a thickness to have a sliding fit in said channelled back, consisting of a plurality of superimposed sheets, a wire stitch binding said sheets together, and a wedge-shaped tongue upon said pad formed by a bayonet slot adjacent, extending at an incline to, and opening outwardly of, the bound edges of said sheets, and so located as to include said wire stitch in said tongue, whereby said tongue is reinforced by said wire stitch and is adapted, by a two-way movement, to interlock with said stud to removably and rigidly connect said pad with said cover.
11. A check book embodying therein a protecting cover including therein a channelled back and opposite side covers, one of which is hinged with relation to said back, and a metal channel piece having extensions at each end of each side, and of the bottom, thereof, folded and crimped upon said channelled back of said cover, and a stud carried by and extending across said channel piece, and a pad of checks of a thickness to have a sliding fit in said channelled back, consisting of a plurality of superimposed sheets, a wire stitch binding said sheets together, and a wedge-shaped tongue upon said pad formed by a bayonet slot adjacent, extending at an incline to, and opening outwardly of, the bound edges of said sheets, and so located as to include said wire stitch in said tongue, whereby said tongue is reinforced by said wire stitch and is adapted, by a two-way movement, to interlock with said stud to removably and rigidly connect said pad with said cover.
12. In a check book, a protecting cover including therein a channelled back, opposite side covers, one of which is hinged with relation to said back, a metal channel piece secured to said channelled back, and a stud carried by and extending across said metal channel piece and adapted to engage a pad of checks and retain them with relation to said cover.
13. In a check book, a protecting cover including therein a channelled back, opposite side covers, one of which is hinged with relation to said back, a metal channel piece secured to said channelled back, and a plurality of studs carried by and extending across said metal channel piece and adapted to engage a pad of checks and retain them with relation to said cover.
14. In a check book, a protecting cover in-
- cluding therein a channelled back, opposite side covers, one of which is hinged with relation to said back, a metal channel piece having extensions at each end of each side, and of the bottom, thereof, folded and crimped upon said channelled back of said cover, and a plurality of studs carried by and extending across said metal channel piece and adapted to engage a pad of checks and retain them with relation to said cover.
15. In a check book, a pad of checks consisting of a plurality of superimposed sheets bound together at one edge thereof and having a bayonet slot formed therein adjacent, and opening outwardly of, the bound edges of said sheets to form a tongue of the material of said pad adapted, by a two-way movement, to interlock with a stud upon a cover to removably and rigidly connect the pad with a cover.
16. In a check book, a pad of checks consisting of a plurality of superimposed sheets bound together at one edge thereof and having a bayonet slot formed therein adjacent, extending at an incline to, and opening outwardly of, the bound edges of said sheets to form a wedge-shaped tongue of the material of said pad adapted, by a two-way movement, to interlock with a stud upon a cover to removably and rigidly connect the pad with a cover.
17. In a check book, a pad of checks consisting of a plurality of superimposed sheets, a wire stitch binding said sheets together, and a tongue upon said pad formed by a bayonet slot adjacent, and opening outwardly of, the bound edges of said sheets, and so located as to include said wire stitch in said tongue, whereby said tongue is reinforced by said wire stitch and is adapted, by a two-way movement, to interlock with a stud upon a cover to removably and rigidly connect the pad with a cover.
18. In a check book, a pad of checks consisting of a plurality of superimposed sheets, a plurality of wire stitches binding said sheets together, and a plurality of wedge-shaped tongues upon said pad formed by bayonet slots adjacent, extending at an incline to, and opening outwardly of, the bound edges of said sheets, and located respectively to include a wire stitch in each of said tongues, whereby each of said tongues is reinforced by a wire stitch and is adapted, by a two-way movement, to interlock with a stud upon a cover to removably and rigidly connect a pad with a cover.
- In witness whereof I have hereunto affixed my signature, in the presence of two subscribing witnesses, this 21st day of December, 1922.
